UNITED STATES PATENT OFFICE.

JOSEPH IMLER, OF KENDALLVILLE, INDIANA.

CROSS-BAR FOR THILLS.

SPECIFICATION forming part of Letters Patent No. 570,021, dated October 27, 1896.

Application filed February 8, 1896. Serial No. 578,523. (No model.)

To all whom it may concern:

Be it known that I, JOSEPH IMLER, a citizen of the United States, residing at Kendallville, in the county of Noble, State of Indiana, have 5 invented certain new and useful Improvements in Cross-Bars for Thills, of which the following is a specification, reference being had therein to the accompanying drawings.

This invention relates to certain new and 10 useful improvements in cross-bars for thills for carriages and wagons and the like; and it has for its object, among others, to provide a simple and cheap construction by which I dispense with the employment of a singletree, 15 reduce the weight of the thill, and have a much stronger cross-bar with less strain on the thill. I also provide an improved hitching device for the tugs of the harness, provide for the automatic take-up of the slack 20 of the tugs when going downhill, and provide a better and more comfortable horse motion than can be obtained by the employment of a singletree.

The cross-bar is designed more particularly 25 for employment in connection with tubular thills, for which I have an application now pending, but is of course applicable to other forms of thills.

I provide means for guarding against rattling of the parts and for ready separation or 30 adjustment where necessary.

Other objects and advantages of the invention will hereinafter appear, and the novel features thereof will be particularly pointed 35 out in the appended claims.

The invention is clearly illustrated in the accompanying drawings, which, with the letters of reference marked thereon, form a part 40 of this specification, and in which—

Figure 1 is a top plan of my improvement, with a portion broken away; and Fig. 2 is an 45 enlarged central vertical section through the hitching device.

Like letters of reference indicate like parts 50 in both views.

Referring now to the details of the drawings by letter, A designates the portions of the thills shown as tubular, and at their rear ends formed with the couplings A', into which 55 the said thills are screw-threaded and into the lateral nipples a of which are threaded

the short pieces of piping B, which in turn are held in the nipples c of the coupling C, in the opposite nipples c' of which is engaged the cross-bar D, which is made tubular, as 55 indicated.

In the nipples c c' of the coupling C are held the short tubular portions E, extending parallel with the thills A, in which are arranged the draft appliances, and as these devices are alike in all respects at each end of the cross-bar a description of one will suffice for both.

F is a rod having at its forward end a hook f for the attachment of the harness-tugs, and 65 this rod is passed through the tubular portions E E and through the longitudinal portions of the coupling C and through openings in the caps G, which are detachably and adjustably held on the outer ends of the tubular 70 portions E.

Washers or packing-rings H may or may not be provided between the outer ends of said tubular portions and the inner faces of the caps, said washers or packing-rings being 75 illustrated in Fig. 2. The rear end of the rod is screw-threaded, as seen at f', and receives a nut F'.

I is a spring arranged around the rod F, with one end bearing against the forward 80 cap or the washer adjacent thereto and the other end connected with the rod in any suitable manner. In Fig. 2 I have shown it as bearing against a pin I', passed through an opening in the rod, the rod being provided 85 with a plurality of openings f'', so that by adjustment of the pin the tension of the spring can be adjusted, as will be readily understood. The tubular portions E, as well as the longitudinal portion of the coupling C, 90 are preferably filled with some suitable packing J, so disposed as to permit of easy movement of the rod lengthwise thereof, but preventing rattling of the parts. This packing may be of any suitable material which will 95 not interfere with the working of the parts or the compression of the spring and yet prevents contact of metal with metal and thus avoids rattling.

It will be noticed that by this construction 100 I dispense with the employment of a singletree, and the attachment of the tugs is such

as to lessen the horse motion, and in going downhill the springs take up the slack in the tugs.

Modifications in detail may be resorted to 5 without departing from the spirit of the invention or sacrificing any of its advantages.

The spring-hook hitching appliance can be used at any suitable place or point on a doubletree or a singletree in connection with carriage or wagon poles.

Having thus described my invention, what I claim as new, and desire to secure by Letters Patent, is—

1. A tubular cross-bar for thills formed of 15 detachable sections and having tubular portions at right angles to its length and draft appliances mounted in said tubular portions; substantially as described.

2. A tubular cross-bar for thills having 20 tubular portions at right angles thereto near opposite ends with removable caps and draft appliances mounted for movement in said tubular portions and through said caps parallel with the thills; substantially as described.

25 3. The combination with the tubular cross-bar, of the couplings at the opposite ends thereof, rods mounted for movement in said couplings at right angles to the cross-bar, and springs around said rods; substantially as described.

35 4. The combination with the tubular cross-bar, of the couplings at the opposite ends thereof, rods mounted for movement in said couplings at right angles to the cross-bar, and springs around said rods, and means for adjusting the tension of said springs; substantially as described.

40 5. The combination with the tubular cross-bar, of the couplings at the opposite ends thereof, rods mounted for movement in said couplings at right angles to the cross-bar, and springs around said rods, and a packing within the coupling to prevent rattling; substantially as described.

45 6. The combination with the tubular cross-bar, of the couplings at the opposite ends thereof, rods mounted for movement in said couplings at right angles to the cross-bar, and springs around said rods, and means for 50 adjusting the tension of said springs, and a

packing within the coupling to prevent rattling; substantially as described.

7. The combination with the tubular cross-bar, of the couplings at the opposite ends thereof, the tubular portions at opposite sides 55 of the couplings at right angles to the cross-bar, removable caps at opposite ends of said coupling rods passed through said tubular portions and through said caps, and couplings and springs around said rods; substantially as described.

8. The combination with the tubular cross-bar, of the couplings at the opposite ends thereof, the tubular portions at opposite sides 65 of the couplings at right angles to the cross-bar, removable caps at opposite ends of said coupling rods passed through said tubular portions and through said caps, and couplings and springs around said rods, and means for adjusting the tension of the springs; substantially as described.

9. The combination with the tubular cross-bar, of the couplings at the opposite ends thereof, the tubular portions at opposite sides 75 of the couplings at right angles to the cross-bar, rods passed through said tubular portions, and couplings and springs around said rods, and means for adjusting the tension of the springs, and caps on the outer ends of said tubular portions and through which the 80 rods pass; substantially as described.

10. The combination with the tubular cross-bar, of the couplings at the opposite ends thereof, the tubular portions at opposite sides 85 of the couplings at right angles to the cross-bar, rods passed through said tubular portions, and couplings and springs around said rods, and means for adjusting the tension of the springs, and caps on the outer ends of said tubular portions and through which the 90 rods pass, said rods being provided at the forward ends with hooks and at their rear ends with adjustable nuts; substantially as described.

In testimony whereof I affix my signature 95 in presence of two witnesses.

JOSEPH IMLER.
